BRONZING AND THE LIKE

Wilfred Waite, London, England, assignor to
 American Machine & Foundry Company, New
 York, N. Y., a corporation of New Jersey

Application May 7, 1937, Serial No. 141,238
 In Great Britain May 18, 1936

12 Claims.

(Cl. 91—59)

This invention relates to bronzing and the like whereby printing or the like is given a bronze or other metallic finish by the application of bronze or like metallic dust or powder (hereinafter referred to as "bronze").

The invention is more particularly applicable to the bronzing of the imprints on cigarette wrapper webs and has for its object to provide an improved apparatus whereby the bronze is applied in a more effective manner than hitherto.

In bronzing the imprints on cigarette wrapper webs it has been usual to apply the bronze dust or powder by the aid of rollers having a plush or like surface which carries the powder and brushes it over the imprint, the excess powder being removed by a subsequent rotary surface or a plurality of such. With this type of apparatus it is found that there is a liability of specks of bronze adhering to the wrapper at places other than where the imprint is located, probably due to the fact that such specks become adhesive by contact with the printing ink as the plush covered rollers move across the imprint, and it is an object of the present invention to apply the bronze in such a way that the above mentioned objection is obviated.

According to the present invention the bronze dust or powder is applied to the imprint on a cigarette wrapper web or other surface by projecting a cloud or spray of bronze dust onto the imprinted surface.

Suction means are preferably provided to carry away and collect excess bronze dust from the zone of application.

The cigarette wrapper or the like in web form may continuously travel past the dusting shower or it may be moved intermittently so as to be stationary during the application of the bronze.

The dusting cloud or spray is preferably produced continuously or intermittently by directing an air blast across the end of a tube the lower end of which projects in a supply of bronze dust.

Further features of the invention will be hereinafter described.

In the accompanying diagrammatic drawings: Figure 1 is a sectional elevation of the improved bronzing mechanism according to one form.

Figure 2 is a partial cross section through the bronzing zone.

Figure 3 shows a modified appliance for forming the bronze spray.

Figure 4 shows a further modification of the spray producing means.

In carrying the invention into effect according

to one mode by way of example as applied to the bronzing of the imprints on a travelling web of cigarette paper, the web 5 bearing imprints in a suitable transparent or other suitable ink on the lower surface, passes from the printer and through a bronzing chamber 6, the web moving preferably in an upwardly inclined direction.

The web seats against a spring surface 7 extending from the entrance 6a to the exit 6b which surface may be formed by a suitable leaf spring 10 mounted upon end supports 8, 9.

Located within the chamber 6 is a container 10 for a supply of the bronze dust or other powder. The container is provided with a cover or lid 11 through which a pipe or nozzle 12 projects so as to extend into the container and also above the lid. The lid 11 is provided with suitable air inlets 13.

A horizontally arranged compressed air pipe 14 is provided, one end (or nozzle) of which is located adjacent the upper end of the bronze pipe or nozzle 12 so that compressed air may blow across the end of such pipe. The other end of the compressed air pipe 14 is connected to a blower 15 or other source of compressed air, the arrangement being such that the compressed air issuing from the horizontal pipe 14 creates a suction in the bronze pipe or nozzle 12 and causes bronze dust to flow through the bronze pipe, the dust being entrained in the spray of compressed air.

The compressed air nozzle may be provided with a divergent or expanding hood 16 to confine the spray, which hood extends up to the paper web.

One or more plush covered rolls 17 having clearing combs 18 may be located within the chamber 6 to clean the web or brush off loose particles of bronze.

Located above the chamber 6 adjacent the spraying zone is a suction hood 19 which is of relatively large capacity for drawing away surplus bronze. The hood seats upon the closure plate 20 (Fig. 2) of the chamber 6 which plate may be recessed to provide a groove 21 in which the leaf spring 7 and the paper web 5 are accommodated. Laterally of the groove 21 the plate is provided with perforations 22 through which the surplus bronze is drawn by suction into the hood 19. The suction hood is also adapted to collect any bronze brushed off by the cleaning rollers 17. The perforations 22 may extend the full length of the hood 19 as seen in Figure 1. The leaf spring may be arranged to assume a longitudinally bowed shape.

35

40

45

50

55

The suction hood 19 may be coupled up to any suitable source of suction and preferably to the inlet of the blower 15 by a conduit 23, a by-pass 24 being provided into which the bronze is adapted to be delivered into a removable container 25.

5 Thus provision is made for recirculation of the air, with such dust as remains in suspension, in a closed circuit which includes the pipe 14, expanding hood 16, perforated plate 20, suction hood 19, conduit 23 and fan 15.

10 In operation, the blower 15 causes compressed air to issue across the bronze nozzle 12 whereby bronze is drawn from the container 10 and entrained in the air to provide a mist or spray past

15 which the web 5 travels, whereby the bronze is projected onto imprints on the web. Excess bronze is drawn off by the suction hood and delivered to the container 25. The web 5 moves past the brushes 17 whereby excess bronze is removed and also drawn off by the suction hood 19.

20 Instead of providing a continuously formed spray or cloud of bronze, a spray may be provided intermittently by means which are synchronised with the printer unit so that a spray or puff is produced each time an imprint moves into the spraying zone. Thus referring to Figure 3 the compressed air pipe 14 may be coupled to a compressed air cylinder 26, the piston 27 of which is operated against a returning spring of 25

30 28 by means of a rotary cam 29 which is driven by suitable means timed with the die shaft of the printer. On each forward stroke of the piston 27 a puff of compressed air issues from the nozzle 14 across the bronze nozzle 12 whereby the 35 desired bronze spray or mist is provided.

35 With such an arrangement, the suction hood 19 for surplus bronze would be operated by a separate unit such as an independent suction fan.

40 Two or more spray devices, which may be operated from a common cylinder, may be provided for producing sprays at spaced zones according to the disposition of the printing.

45 According to a further form, see Figure 4, the intermittent jets of compressed air may be provided by a bellows device 30 operated by a rotary cam 31 driven in timed relation to the die shaft of the printing unit.

50 While the invention has been particularly described with reference to a cigarette web which continuously moves through the bronzing zone, it will be obvious that the web may have intermittent movement so that it is stationary during the bronzing operation. Moreover, the 55 invention may be applied to bronzing of running or intermittently moving webs other than cigarette wrapper webs, whether or not the printing or the like to be bronzed is arranged at spaced intervals or is of a more or less continuous 60 nature. Further it will be obvious that any other dusting powder, metallic or otherwise, may be used instead of bronze.

I claim:

1. Apparatus for bronzing the imprints on a 65 cigarette wrapper or other web, comprising a chamber, means for passing the web through an upper zone of the chamber, a container for bronze dust below the path of the web within said chamber, a tube projecting from said container toward said path, a spray confining hood 70 into which the upper end of said tube projects, a conduit extending into the hood and located to direct compressed air across the upper end of said tube and means for supplying compressed air to said conduit.

2. Apparatus for bronzing the imprints on a cigarette wrapper web as claimed in claim 1 wherein suction means are provided above said path for collecting excess bronze dust.

3. Apparatus for bronzing the imprints on a cigarette wrapper web as claimed in claim 1 wherein said spray is directed toward the middle of the traveling web and is deflected laterally thereby, and said chamber has a perforated wall adjacent the path of the web, at each side thereof, above the spraying zone, and a suction hood located outside the chamber and extending over said perforated wall for collecting exhaust bronze dust.

4. Apparatus for bronzing the imprints on a cigarette wrapper or like web as claimed in claim 1 wherein a cylinder is provided for intermittently supplying compressed air to said conduit, and means for reciprocating the piston of said cylinder, whereby the dust is impacted by a puff of air at each application of said dust.

5. Apparatus for bronzing the imprints on a cigarette wrapper web as claimed in claim 1 wherein rotary brushes and complementary combs are located within the chamber and cooperate to recover excess bronze dust from the web.

6. Apparatus for bronzing the imprints on a cigarette wrapper web as claimed in claim 1 wherein the upper wall of said chamber is provided with a longitudinally extending groove, a leaf spring located in said groove and providing a seating surface for the web in its passage through the chamber.

7. Apparatus for bronzing the imprints on a cigarette wrapper or other web, comprising a chamber, means for passing a web of indefinite length continuously through an upper zone of the chamber in an upwardly inclined direction, means within the chamber for creating a spray of bronze dust and projecting it from beneath onto the imprints on the under surface of the traveling web, means to overlie the web to support it against the air pressure, and means to guide the web along its traveling margins.

8. Apparatus for bronzing the imprints on a cigarette wrapper or other web, comprising a chamber, means for passing a web of indefinite length continuously through an upper zone of the chamber in an upwardly inclined direction, means within the chamber for creating a spray of bronze dust and projecting it from beneath onto the imprints on the under surface of the traveling web, means to overlie the web to support it against the air pressure, means to guide the web along its traveling margins, and means acting upon said under surface to remove the excess of bronzing medium.

9. Apparatus for bronzing the imprints on a cigarette wrapper or other web, comprising a chamber, means for passing a web of indefinite length through the chamber in a substantially straight run, with the imprints facing downwardly, means within the chamber for creating a spray of bronze dust and projecting it in a stream upward against the imprints on the web, and complementary pneumatic means for sucking the dust-laden stream around said web, said means being constructed and arranged to apply said dust-laden stream recurrently to said web by a current of air recirculated past the web, in a closed circuit to which increments of dust are added automatically.

10. Apparatus for bronzing the imprints on a cigarette wrapper or other web, comprising a chamber, means for passing the web through an

- upper zone of the chamber, a container for bronze dust within said chamber, a tube projecting from said container toward the under surface of the web, a conduit disposed in position to direct a blast of air across the upper end of said tube, and means for supplying compressed air to said conduit, thereby creating an inspirated stream of dust and projecting the same directly against said imprints.
- 5 10 11. Apparatus for bronzing the imprints on a cigarette wrapper or like web as claimed in claim 7, wherein said spray is directed toward the middle of the traveling web and is deflected laterally thereby, and said chamber is provided with
- 15 a perforated wall adjacent to the path of the web, at each side thereof, above the spraying zone, a suction hood located outside the chamber and extending over said perforated wall, said means for supplying compressed air to said conduit including a fan having its inlet coupled to
- 20 said suction hood, said fan, spray tube, spray-confining hood and return conduit cooperating to maintain a circulation of air past the web, by which pulverulent matter, such as bronzing, is applied in a closed circuit to the under surface 5 of the web and thence in due course is withdrawn from the upper zone of the mechanism.
12. Apparatus for bronzing the imprints on a cigarette wrapper as claimed in claim 7 wherein the web passes through the chamber along 10 an upwardly inclined path, said means for spraying the bronze dust being directed toward the under surface of the web, and said spraying means including an impeller adapted to project dust-laden air intermittently in puffs against said 15 imprints, whereby an adequate amount is supplied to charge the imprints, and any excess is blown away from the web.
